UNITED STATES PATENT OFFICE.

HENRY L. PITMAN, OF WESTFIELD, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed June 19, 1922. Serial No. 569,291.

To all whom it may concern:

Be it known that I, HENRY L. PITMAN, a citizen of the United States, residing in Westfield, in the county of Union and State 5 of New Jersey, have invented certain new and useful Improvements in Typewriting Machines, of which the following is a specification.

This invention relates to the application 10 of mechanism of the continuous billing or fan-fold type to a bookkeeping machine of the Underwood-Hanson type and is in the nature of an improvement on the inventions disclosed in the applications of B. C. Stickney, Serial No. 489,990, filed August 5, 1921, and Serial No. 562,969, filed May 23, 1922.

When fan-fold mechanism is applied to a bookkeeping machine of the type referred to, the webs must be guided above certain 20 parts of the computing mechanism located at the rear of the typewriter-carriage and usually projecting somewhat above the rear edge of the paper-table forming part of said carriage. The usual webs are, therefore, introduced at such a height above the platen that it is difficult to straighten them sufficiently to retract the carbons. Further difficulties arise in providing for access to the 25 denomination-selectors and other parts at the rear of the typewriter-carriage, and in providing means for supporting the rail on which the rearward extension of the carriage travels.

The main object of the invention is to provide new and improved means for avoiding the above and other difficulties arising from the application of fan-fold mechanism to bookkeeping machines.

In the embodiment of the invention herein disclosed, use is made at each end of the platen of an oversized broad pinion for connecting a gear on the adjacent end of the platen-axle with a similar gear on a stub-shaft journaled in the adjacent end of the carriage. By using the oversized broad pinions, it is rendered possible to locate the axis, about which the broad pinions turn and about which the platen-lifting frame swings, at such an elevation that the platen may be displaced upwardly to a greater extent than in the ordinary fan-fold machine.

In the usual form of fan-fold machines, the ends of the platen-lifting frame are con-

nected by a tie-member or rod which extends along the axis about which the platen-lifting frame swings. If, however, this tie-member were used in the machine embodying the present invention, it would interfere both with the view of the work being typed and also with the handling of work extending around the platen. To avoid such objections, the usual tie-member is omitted and, in its place, provision is made of a tie-member or rod connecting the ends of the platen-lifting frame behind the usual collating table and adjacent the platen. It will be evident that a tie-rod in the position described will not interfere in any way with the view of the work and access thereto.

The rearward extension of the carriage on which the usual carbon-carrier is mounted may consist of a continuous apron or guard extending over the denomination-selecting mechanism at the rear of the typewriter-carriage and having its forward edge adjacent the upper edge of the rear paper-table, and may be so mounted on a rail at the rear of the bookkeeping machine that it may swing upwardly to remove the apron from its position above the denomination-selecting elements, thereby rendering such elements accessible. Preferably the rearward extension of the carriage comprises a continuous sheet or plate of metal of which the forward end constitutes the apron, referred to, and guides the webs to the rear paper-table, the remainder of the extension being cut away to make the structure lighter, and being provided at its side and rear edges with flanges to stiffen it. Provision may be made of rails of the usual type secured to the upper face of the extension and serving to support and guide the usual carbon-carrier.

The rear rail, upon which the carbon-carrier-extension of the carriage is supported, 95 may be held in position by brackets connected to the usual stand on which the bookkeeping machine rests, the connection between the rearward extension of the carriage and the rail being such that the former may 100 be swung upwardly about the latter. In order to prevent the rearward extension from being swung too far upwardly and rearwardly, provision is made of suitable means to prevent such excessive movement. 105 Such preventing means may be of any suit-

able form, such as a chain connected at one end to the extension and at the other end to the stand of the bookkeeping machine, sufficient slack being provided to permit the necessary amount of swing of said rearward extension.

Provision may also be made for locking the rearward extension of the carriage in its normal position.

10 In order that friction between the rearward extension of the carriage and the rail on which the rear extension rests at its rear may be diminished, provision may be made of suitable friction-reducing means, such as 15 ball-bearing-mountings for the wheels running on said rail. Provision may also be made of means associated with said mountings to hold the rearward extension of the carriage on the rear rail when it is swung 20 upwardly.

Other features and advantages will hereinafter appear.

In the accompanying drawings,

25 Figure 1 is a diagrammatic side view, partly in section, showing the invention applied to a bookkeeping machine of the Underwood-Hanson type.

30 Figure 2 is a detail view, partly in section, showing the manner of mounting the wheels by which the rearward extension of the carriage is supported on the rear rail.

35 Figure 3 is a view from the right of the parts shown in Figure 2.

Figure 4 is a view, from above, of the parts shown in Figure 2.

Figure 5 is a top plan view of the machine, certain parts being omitted and the platen being shown in its normal position.

40 Figure 6 is a rear elevation of the machine.

Figure 7 is a view showing sections, taken along lines *a—a* and *b—b*, of Figure 6.

45 Figure 8 is a view showing means for locking the carbon-carrier-extension in effective position, the position of the parts being such as to permit lifting of the front end of the extension.

Figure 9 is similar to Figure 8, but shows the parts in locking position.

50 Figure 10 is a top plan view of the portion of the locking means at the left of the rearward extension of the carriage, parts being broken away to show the underlying structure.

55 Figure 11 is a fragmentary, sectional view, showing the manner of mounting one of the broad pinions and one of the ends of the platen-displacing frame.

60 Figure 12 is a diagrammatic side view, showing the rearward extension of the carriage swung upwardly to its limiting position.

65 Figure 13 is a fragmentary, perspective view, showing the rearward extension of the carriage in its normal position, certain of

the parts being shown in spread relation to make clear the manner of attaching the carbon-carrier-rails to said extension.

A platen 11 is revolvably mounted in a carriage 12 supported at its front by a roller 70 13 projecting into a groove in a cross-bar 14, and at its rear by a rail 15, said cross-bar 14 and rail 15 being fixed on a typewriter-frame 16.

The typewriter-frame 16 is mounted on a 75 computer 17, which, in turn, rests on a stand 18, comprising a top 19 and legs 20. To insure proper positioning of the computer 17 on the stand 18, the top 19 is provided with socket-members 21, having tapered openings 22, into which fit tapered feet 23 of the computer. It will be evident that the movement of the tapered feet 23 into the socket-members 21 will insure the proper positioning of the computer 17 on 80 the stand 18.

Provision is made at the rear of the carriage of a rear paper-table 24 and rearwardly-extending brackets 25 to support a rack 26 to receive, at letter-space distances, 90 a tabulator-stop 27. Projecting outwardly and upwardly from the rear ends of brackets 25 are brackets 28, in which are supported the ends of a rod 29, on which a denomination-selector 30 is mounted for 95 swinging and sliding movements, the selector being held in any selected letter-space position along the rod 29 by means of a tooth 31 engaging in the proper notch of a series in a rod 32, said notches being at 100 letter-space distances apart along said rod 32. It should be understood that, although reference has been made to one tabulator-stop and one denomination-selector, a plurality of each of these elements may be used 105 when required.

A denominational jack-housing 33 is supported at the rear of, and above, the denomination-selector 30 by means of a transverse bar 34 supported by brackets 35 extending rearwardly and upwardly from the typewriter-frame. Extending downwardly from the rear of the denominational jack-housing 33 to the lower rear portion of the computer 17 is a casing 36 for the usual 110 thrust-rods, not shown. Obviously, a plurality of sets of jacks and housings therefore may be provided, and, as shown in Figure 6, the machine herein disclosed is a three-register machine and has three sets of 115 jacks and three housings.

The computing mechanism and the denomination-selecting mechanism, forming part thereof, may be, in general, similar to that disclosed in the patent to Richard M. Becker, No. 1,296,355, granted March 4, 1919.

The present invention contemplates the application of fan-fold mechanism to a 120 bookkeeping machine, such as that of which 125

a partial description has been given. To this end, provision is made of a rearward extension 37 of the carriage 12, on which is mounted for forward and rearward sliding movement a carbon-carrier 38, moved forwardly with a web 39 as the latter is fed around the platen, and moved rearwardly by means of a handle 40 to withdraw the carbon-sheets, not shown, when the web is straightened under the platen.

The extension 37 is formed preferably of a single sheet of metal, and comprises a forward continuous portion or guard 41, suitably curved to guide the web 39 over the housing 33, and other parts at the rear of the upper edge of the rear paper-table 24. At the rear of the continuous portion 41, the extension 37 is cut away, as shown in Figure 13, to reduce the weight, and is provided at its side and rear edges with flanges 42 to strengthen it.

Mounted along the edges of the extension 37 are rails 43, which serve to guide and support the carbon-carrier 38. Preferably the rails 43 are spaced from the upper surface of the extension 37 by means of spacers or washers 44, at suitable intervals, and the rails are secured to the extension by means of screws 45 passing through openings 46 and through the spacers 44 into threaded openings 47 in said extension. The carbon-carrier 38 may be supported on the rails 43 by grooved rolls 48 pivoted on the carbon-carrier 38, and engaging the rails 43 on opposite sides thereof. As shown in Figures 1 and 13, the forward screw 45 for the left-hand rail may be provided with a head which will project upwardly above the surface of the rail to serve as a stop to limit the forward movement of the carbon-carrier; and, as shown in Figure 5, the left-hand rail 43 may be provided with a scale 49 to assist in positioning a stop, not shown, for limiting the rearward movement of the carbon-carrier 38.

In the normal operation of the machine, the extension 37 travels with the carriage 12, and for such movement runs on a rail 50, positioned beneath the same and near the rear edge thereof. The rail 50 is attached at its front to lips 51 formed on plates 52 secured to the upper ends of brackets 53, which are secured at their lower ends to the top 19 of the stand 18 on which the book-keeping machine rests. Each of the brackets 53 is formed as a channel-iron and gradually increases in size from its upper end to its lower end, where it is attached to the stand 18. Preferably, a portion of each bracket at the base of the channel is cut away to diminish the weight. At their lower ends the brackets 53 are formed so as to fit around the upper surface of the top 19 and the rear surface of a downwardly-extending flange 54 forming part of the top 19, each bracket

being attached to the top 19 by suitable means, such as a vertical screw or bolt 55 extending through the horizontal portion of the top, and by horizontal bolts 56 extending through the flange 54. The brackets may be connected near their lower ends by a bar 57, for a purpose to be described hereinafter.

To avoid unnecessary friction between the extension 37 and the rail 50 as the former travels along the latter, provision may be made, at each side of the extension 37, of a pair of cones or rolls 58, each having a frusto-conical portion 59 to run on the rail 50. The rolls 58 of each pair are annular in form and are mounted by suitable ball-bearings on a block 60, secured to the adjacent side flange 42 by any suitable means, such as screws 61. Passing through the block 60 is a bolt 62, threaded at each end and carrying at each side of the block 60 a cone or bearing member 63, having a conical surface, to co-operate with balls 64 in a groove or raceway 65 of the adjacent roll 58 mounted on the bolt 62, and, at the outer side of each of the rolls 58, a cone or bearing member 66 having an inwardly-facing conical surface, to engage the balls 64 on the side opposite to that engaged by the corresponding member 63, the parts being held in position by means of nuts 67 on opposite ends of the bolt 62. It will be seen that each pair of rolls 58 serves to give a bearing extending around a sufficient portion of the rail 50 to avoid a tendency to run off the rail 50.

To insure engagement between each pair of rolls 58 and the platen, provision is made of a member 68 having a horizontal portion 69 held by a screw 70 against a shoulder 71 formed by cutting away a portion of the upper part of the block 60 at its inner end. Each member 68 also comprises a portion extending down the inner face of the corresponding block 60, and secured thereto by a screw 72, and a curved portion 73 extending around the rail 50 to the bottom thereof. It will be seen that the extension 37 is so mounted on the rail 50 that it may be swung upwardly and rearwardly about said rail 50 without being disconnected therefrom, thereby permitting access to the denomination-selecting mechanism at the rear of the carriage to permit adjustment of the parts, such as the positioning of the denomination-selecting mechanism 30 along the rods 29 and 32. The extension 37 may be swung from its normal position, shown in Figure 1, to the position shown in Figure 12, the upward movement of the extension being limited preferably by means of a chain 74 connected at its lower end to the bar 57, which connects the rail-supporting brackets, and, at its upper end, to a ring 75 surrounding a rod 76, which is connected at its ends with the side flanges 42 of the extension 37.

4
It should be understood that the chain 74 is of sufficient length so that the extension, when in its limiting position, Figure 12, will be held in such position by means of gravity.

To cause the extension 37 to travel with the carriage and to prevent accidental movement of the extension 37 upwardly from its normal position, provision may be made of means to lock the forward end of the extension to the carriage 12. To this end, provision is made of brackets 77 and of suitable bearing-members 78 secured to the upper ends of said brackets 77. As shown in Figures 8 and 9, the bearing-members 78 have circular openings 79 in alignment with each other, and each of said members 78 is provided with a vertical slot 80 extending downwardly from its upper surface to the circular opening 79, the width of the slot 80 being less than the diameter of the circular openings 79. To co-operate with the bearing-members 78, provision is made of a shaft 81, mounted in brackets 82, attached to the portion 41 of the extension 37 on the under side thereof, the shaft 81 being of suitable diameter to fit in the openings 79 of the bearing-members 78, and being cut away on opposite sides thereof near its ends, to form flats 81^a, so that, when the shaft is in proper rotative position, the cut-away ends may be passed through the slots 80 in the bearing-members 78, as indicated in Figure 8, and turned to the position indicated in Figure 9, thereby locking the extension 37 to the carriage 12.

Normally, the shaft 81 is urged in a locking direction by means of a spring 84 connected, as shown in Figure 5, at its left end to the shaft 81, and at its right end with the extension 37. To limit the movement of the shaft 81 in opposite directions, provision is made of arcuate members 85 extending partially around the shaft 81 adjacent the brackets 82 and secured to the shaft 81 by any suitable means, such as screws 86. As shown in Figure 8, the forward end of each member 85, when brought into contact with the lower surface of the guard 41, will position the shaft 81 so as to permit its removal from the bearing-members 78, the shaft, when released to the action of the spring 84, being turned to the locking position shown in Figure 9, with the other ends of the members 85 contacting with the portion 41. At its outer ends, the shaft 81 is provided with collars 87 contacting with the outer surfaces of the bearing-members 78, and also with collars 88 engaging the bearing-members 78 at the inner sides thereof. The collars 87 and 88 may be detachably secured on the shaft 81 by screws 87^a and 88^a, respectively.

Preferably, the left-hand collar 88 is provided with a finger 89, which may serve as

a left side gage or guide for work passing over the extension 37 to the rear paper-table. Provision is also made of a finger or guide 90 projecting from the right-hand collar 88. Preferably, the finger 90 is of greater length than the finger 89 and may serve not only as a right side gage or guide for the work, but also as a finger-piece for turning the shaft 81 against the action of the spring 84 to the position shown in Figure 8, so that the rearward extension 37 of the carriage may be swung upwardly to the position shown in Figure 12.

At the rear of the extension 37 of the carriage, the web passes over a rod or guide 91 immediately above the rear edge of the extension, and the web may be guided at its side edges by side guides or gages 92, of which the left gage is provided with an overhanging portion 93 to prevent the adjacent edge of the web from being thrown above the top of the guide. Each of the gages or guides 92 is provided with a collar 94, which may be secured to the rod 91 at any desired position therealong by means of a set-screw 95. Preferably, the rod 91 is provided with a depression 96, for each position to which the guides are to be adjusted, said depressions being of suitable size to receive the lower ends of the set-screws 95. The outer depressions are so positioned as to locate the side gages 92 substantially in alignment with the respective fingers 89 and 90. Each end of the rod 91 is secured to an upright arm 97 of a bracket 97^a, having a horizontal arm 98 lying against the lower surface of the extension 37 and secured thereto by any suitable means, such as rivets 99. It will be seen that side flanges 42 are cut away near their rear ends to permit the passage of the horizontal arms 98 of the bracket 97^a.

As shown in Figure 1, the forward ends of the flanges 42 of the extension 37 are cut away to form inclined edges following the general outline of the top of the housing 33, thereby permitting the extension 37 to be placed lower than could otherwise be done. It should also be noted that the guard 41 is arched upwardly above the plane of the main portion of the extension 37 so as to pass over the upper edge of the housing 33. The arrangement just described is such that the web 39, in passing over the forward edge of the housing 33, and that the portion of the extension on which the carbon-carrier 38 runs is lower than the top portion of the guide to such an extent that the web 39 will pass substantially horizontally from the carbon-carrier 38 to and over the guard 41.

Notwithstanding that the fan-fold mechanism at the rear of the carriage is so designed as to guide the web 39 over the denomination-selecting mechanism at as low

a level as possible, it is necessary to displace the platen 11 upwardly to a greater extent than in the ordinary fan-fold machine, to permit the web 39 to be straightened under the platen. To this end, provision is made of suitable bars or members 100, secured to ends 101 of a platen-frame 102 forming part of the carriage 12. The members 100 lie against the inner faces of the ends 101 and may be secured to said ends by means including bolts 103 inserted from the inside of members 100 through openings in the members 100 and ends 101 and threaded into nuts 104 on the outer sides of the ends 101. Inasmuch as the platen is to be lifted to an abnormal extent, each one of the members 100 is provided at its forward end with an upwardly and forwardly projecting bracket 105 to provide suitable pivotal supports for the ends 106 of a platen-displacing frame 107. The ends 106 of the platen-displacing frame 107 have arms substantially at right angles to each other, one arm 109 of each of said ends 106 being pivoted to the adjacent bracket 105, and the platen 11 being supported in said frame 107 by means of a platen-axle 108 journaled in the ends 106 substantially at the vertices of the right angles formed by the arms 109 and 110 of the ends 106. The arms 110 are joined by a tie-member 111 and, when the platen-displacing frame 107 is in its normal position with the supports 112 at the outer ends of the arms 110 resting on a shaft 113 extending across the carriage at the rear of the rear paper-table 24, studs or pins 111^a projecting from the arms 110 will be engaged and held by hooks 114 fixed on the shaft 113 which is normally urged by a spring 115 to effective position, thus locking the frame 107 in its normal position. The hooks 114 may be swung rearwardly to ineffective position, when desired, by means of a finger-piece 115^a extending upwardly from the left-hand hook.

To turn the platen, provision is made of a gear 116 fixed on each end of the platen-axle 108, just outside of the adjacent end 106 of the displacing frame 107; and of a similar gear 117 fixed on the inner end of a stub-shaft 118 journaled in the adjacent end of the carriage in alignment with the normal position of the platen-axle. Both of the gears 116 and 117 are constantly in mesh with a broad pinion 119 mounted coaxially with the pivots about which the platen-displacing frame 107 swings so that the connection between the gears 116 and 117 and the broad pinions 119 will be maintained, irrespective of the position of the platen-displacing frame. The platen may be rotated by means of finger-wheels 120 on the stub-shafts 118, or by suitable line-spacing mechanism, not shown. Due to the provisions for displacing the platen upwardly to an ab-

normal extent, the pinions 119 are correspondingly larger than the corresponding pinions in the usual machine and may be described as oversized.

When the platen 11 is displaced upwardly, the gears 116 will be carried upwardly therewith, but the gears 117 will still prevent access to the slotted heads 121 of the bolts or screws 103. This difficulty is overcome, however, by providing openings 122 in gears 117, so that, when the latter are rotated to the proper positions by one of the finger-wheels 120 or otherwise, a suitable tool, such as a screw-driver, may be passed through either one of the openings 122 and engaged in the slot of the corresponding head 121 and the screw, forming part of the latter, turned as desired.

Preferably the mounting of each end 106 of the platen-displacing frame 107 and of the adjacent broad pinion 119 is as follows: A bushing 123 is secured in an opening 124 of the adjacent bracket 105, and through a central opening in said bushing is inserted a bolt or screw 125, which extends through the hub 126 of the broad pinion 119 and is provided with a threaded end 127 of reduced size, which is screwed tightly into a boss 128 fastened on the adjacent end 106 of the platen-displacing frame. It should be understood that the pinion 119 turns freely on said bolt 125.

In fan-fold machines of the usual form, the ends 106 of the platen-displacing frame 107 are joined by a tie-member substantially coaxial with the pivots about which the platen-displacing frame swings. Due to the abnormal height, with reference to the platen, of the pivots (screws 125) of the platen-displacing frame, a tie-member of the usual form would interfere with the view of the work. According to the present invention, no such tie-member is used, and, to stiffen the platen-displacing frame otherwise, provision is made of a tie-rod 129 connecting the two ends 106 and passing to the rear of the usual collating table 130 and close to the platen. A gage-bar 131 of the usual form is secured to the back of the collating table 130, and is provided with an adjustable end-gauge 132 of the usual form.

Provision is made of a knife 133, pivotally mounted on the platen-axle, to facilitate the tearing-off of used sections of the web, and preferably the knife, instead of being flat, as in the usual form, is turned away from the platen at its rear edge to form a flange 134, thus keeping the knife sufficiently strong, while decreasing its width and thereby avoiding interference with the view of the work by the rear edge of the knife. The knife 133 is supported on arms 135 pivotally mounted on the platen-axle and may be swung away from the platen 11 by means of a finger-piece 136 (Figure 5).

Furthermore, the arrangement of the various parts to permit the abnormal upward displacement of the platen renders it inconvenient to limit the forward position of the platen-displacing frame 107 in the usual manner by resilient stop-members extending upwardly from the transverse bar 137 at the front of and forming part of the carriage 12. Provision is therefore made of brackets 138, one at each side of the carriage, secured at their forward ends to the bar 137 by any suitable means, such as screws 139, and at their rear ends fitting over the hubs 126 of the broad pinions 119. Each of the brackets 138 is provided with an upward extension at its rear end, said upward extension having a tooth 140 projecting therefrom to engage the forward edge of the arm 109 of the adjacent end of the platen-displacing frame 107, to stop the latter in the position shown in Figure 1.

When it is desired to set a denomination-selector 30 to determine the position of a computing zone, the finger-piece 115^a is shoved to the rear to release the platen-displacing frame 107 from the hooks 114, and the frame 107 is swung forwardly to the position shown in Figure 1. The finger or finger-piece 90 is then pushed to the rear to turn the shaft 81 to its releasing position shown in Figure 4, so that the rearward extension 37 of the carriage may be swung upwardly until it reaches its limiting position determined by the chain 74, as shown in Figure 12; the length of the chain being such that the extension 37, when swung to its Figure 12 position, will be held in such position by gravity. The denomination-selector 30 may then be swung upwardly about the rod 29, and adjusted therewith, as shown in Figure 12. When such adjustment is completed, the denomination-selector is swung down to the position shown in Figure 1, and the extension 37 restored to and locked in its normal position.

It will be evident that, according to the present embodiment of the invention, provision has been made of means for the purpose described which enables the web to be fed over the raised forward edges of the housings 33 at a very slight distance thereabove, and that the new parts are so designed as to be readily applicable to fan-fold machines now in use.

55 Variations may be resorted to within the scope of the invention, and portions of the improvements may be used without others.

Having thus described my invention, I claim,

60 1. In a machine of the class described having a platen, a carriage therefor, comprising a forwardly and downwardly inclined rear paper-table, and denomination-selecting mechanism projecting above said paper-table at its rear, fan-fold mechanism

including a carbon-carrier and a rearward extension of the carriage having a continuous guard portion extending over the denomination-selecting mechanism and arched so as to have its forward edge adjacent the upper edge of the rear paper-table and its rear portion below the level of the top of the denomination-selecting mechanism, and a carbon-carrier-track portion extending rearwardly from said guard portion at such a level that the web passes substantially horizontally from the carbon-carrier over the guard.

2. In a machine of the class described having a platen, a carriage therefor, comprising a forwardly and downwardly inclined rear paper-table, and denomination-selecting mechanism projecting above said paper-table at its rear, fan-fold mechanism including a carbon-carrier and a rearward extension of the carriage having a continuous guard portion extending over the denomination-selecting mechanism and arched so as to have its forward edge adjacent the upper edge of the rear paper-table and its rear portion below the level of the top of the denomination-selecting mechanism, and a carbon-carrier-track portion extending rearwardly from said guard portion at such a level that the web passes substantially horizontally from the carbon-carrier over the guard, said rearward extension having side flanges to strengthen the same, and said flanges being cut away at the front so that the guard portion may take up as little space as possible above the denomination-selecting mechanism.

3. In a typewriting machine of the fan-fold type, the combination with a traveling carriage having a rear paper-table, of a rearward extension of said carriage consisting of a single plate having its forward edge in position to co-operate with the rear edge of the rear paper-table in guiding webs to the platen, and a carbon-carrier mounted on said extension.

4. In a typewriting machine of the fan-fold type, the combination with a traveling carriage having a rear paper-table, of a rearward extension of said carriage consisting of a single plate having its forward edge in position to co-operate with the rear edge of the rear paper-table in guiding webs to the platen, said plate having its edges turned at right angles thereto to form strengthening flanges therefor, and a carbon-carrier mounted on said extension.

5. In a typewriting machine of the fan-fold type, the combination with a traveling carriage having a rear paper-table, of a rearward extension of said carriage consisting of a single plate having its forward edge in position to co-operate with the rear edge of the rear paper-table in guiding webs to the platen, a carbon-carrier to recipro-

cate on said extension, and rails for said carbon-carrier mounted on said extension at opposite sides thereof.

6. In a typewriting machine of the fan-fold type, the combination with a traveling carriage having a rear paper-table, of a rearward extension of said carriage consisting of a single plate having its forward edge in position to co-operate with the rear edge 10 of the rear paper-table in guiding webs to the platen, a carbon-carrier to run on said extension, said carbon-carrier having grooved rolls pivoted on the lower side thereof, rails on opposite sides of the extension 15 having edges to enter the grooves of said rolls, and spacers to hold said rails above said extension.

7. In a typewriting machine of the fan-fold type, the combination with a traveling carriage having a rear paper-table, of a rearward extension of said carriage consisting of a single plate having its forward edge in position to co-operate with the rear edge 20 of the rear paper-table in guiding webs to the platen, said plate having its edges turned at right angles thereto to form strengthening flanges therefor, and the flanges at the sides being cut away at their forward ends to permit the normal position 25 of the forward end of the extension to be lower than would otherwise be the case, and a carbon-carrier mounted on said extension. 8. In a typewriting machine of the fan-fold type, the combination with a traveling carriage having a rear paper-table, of a rearward extension of said carriage consisting of a single plate having its forward edge 30 in position to co-operate with the rear edge of the rear paper-table in guiding webs to the platen, a carbon-carrier to run on said extension, said carbon-carrier having grooved rolls pivoted on the lower side thereof, rails on opposite sides of the extension 35 having edges to enter the grooves of said rolls, spacers to hold said rails above said extension, and screws passing through said rails and said spacers to hold the rails on the plate, one of said screws having a head extending upwardly above the corresponding rail to serve as a front stop for 40 said carbon-carrier.

9. In a typewriting machine of the fan-fold type, the combination with a carriage, of a platen, and a platen-displacing frame comprising ends pivoted on said carriage to the front of the normal position of the platen to permit the latter to be swung upwardly and forwardly, a collating table 45 mounted on said ends in position to receive work from the platen, and tie-members to connect said ends, all of said tie-members being at the rear of the collating table, thereby leaving the platen-displacing frame open at the front of the platen to avoid interference with a view of the work.

10. In a machine of the class described having at its rear upwardly-projecting denomination-selecting mechanism over which the work is fed to the typing mechanism, the combination with a carriage, of 70 a displaceable platen, a collating table at the delivery side of said platen, gears at each end of the platen normally in alignment and respectively attached to the platen and journaled in the adjacent end of 75 the carriage, an oversized broad pinion pivoted at each end of the carriage, and a platen-displacing frame having ends in which the platen is journaled and which are pivoted coaxially with said broad 80 pinions so as to maintain the engagement between the broad pinions and the gears, said collating table being mounted on the ends of the displacing frame, and connecting members extending between the ends of 85 the displacing frame, all of said connecting members being located at the rear of the collating table to avoid interference with a view of the work, which, due to the high elevation of the pivots of the displacing 90 frame, would result if any of said connecting members were positioned in front of the platen and collating table.

11. In a machine of the character described, the combination with a traveling carriage, of a rearward extension thereof on which a reciprocable carbon-carrier travels, a rail on which the rearward portion of said extension travels in its movement with the carriage, a finger-piece, means controlled by said finger-piece to lock the extension to said carriage to travel therewith or to permit it to be detached from the carriage and swung upwardly 95 about said rail, and means for limiting the upward and rearward swinging movement of the extension, said limiting means permitting the extension to be swung about the rail sufficiently to be retained by gravity 100 in its limiting position. 110

12. In a machine of the character described, the combination with a traveling carriage, of a rearward extension thereof on which a reciprocable carbon-carrier travels, a rail on which the rearward portion of said extension travels in its movement with the carriage, a finger-piece, and means for detachably connecting said extension to the carriage, whereby the former may be connected with the latter to travel 115 therewith or may be released therefrom and swung upwardly about said rail, said connecting means comprising a member on said carriage having a cylindrical opening therethrough and a comparatively narrow radial slot extending from the outside of said member to said opening, and a rotatable shaft provided with opposite flat parallel surfaces at such distance apart as to permit its entrance through said slot, said 120 125 130

rotatable shaft being locked against withdrawal through said slot by turning it after such insertion.

13. The combination with a stand for a combined typewriting and computing machine having applied thereto fan-fold mechanism including a carbon-carrier track, said stand comprising a top having a depending flange at its rear edge, of a rail to support 5 said carbon-carrier track at its rear, and means to support said rail comprising, at each side of the stand, a bracket attached to said rail at its upper end and gradually increasing in size from its upper end to its 10 lower end, said lower end being shaped to fit over the rear edge of said top so as to rest on the upper surface of the top and also on the rear face of the flange.

14. The combination with a stand for a combined typewriting and computing machine having applied thereto fan-fold mechanism including a carbon-carrier track, said stand comprising a top having a depending flange at its rear edge, of a rail to support 20 said carbon-carrier track at its rear, means to support said rail comprising, at each side of the stand, a bracket attached to said rail at its upper end and gradually increasing in size from its upper end to its 25 lower end, said lower end being shaped to fit over the rear edge of said top so as to rest on the upper surface of the top and also on the rear face of the flange, and means to secure each of said brackets to the 30 horizontal portion of said top and also to said flange.

15. The combination with a stand for a combined typewriting and computing machine having applied thereto fan-fold mechanism including a carbon-carrier track, said stand comprising a top having a depending flange at its rear edge, of a rail to support 40 said carbon-carrier track at its rear, and means to support said rail comprising, at each side of the stand, a bracket attached to said rail at its upper end and gradually increasing in size from its upper end to its lower end, said lower end being shaped to fit over the rear edge of said top 45 so as to rest on the upper surface of the top and also on the rear face of the flange, each of said brackets being of channel shape in 50 cross-section.

16. In a typewriting machine of the fan-fold type, comprising a carriage, a carbon-carrier, and a rearward extension of the carriage on which said carbon-carrier is reciprocable, the combination with said extension, of a rail of circular cross-section, and means 55 to support and guide said extension on said rail, said supporting and guiding means comprising a block, and inwardly-facing conical rolls pivotally mounted on opposite sides of said block and resting on said rail on 60 opposite sides of the upper portion thereof.

17. In a typewriting machine of the fan-fold type, comprising a carriage, a carbon-carrier, and a rearward extension of the carriage on which said carbon-carrier is reciprocable, the combination with said extension, 70 of a rail of circular cross-section, means to support and guide said extension on said rail, said supporting and guiding means comprising a block, and inwardly-facing conical rolls pivotally mounted on opposite 75 sides of said block and resting on said rail on opposite sides of the upper portion thereof, and a guard mounted on said block and extending around the bottom of said rail to prevent disengagement of the rolls from the 80 rail.

18. In a typewriting machine of the fan-fold type, comprising a carriage, a carbon-carrier, and a rearward extension of the carriage on which said carbon-carrier is reciprocable, the combination with said extension, 85 of a rail of circular cross-section, means to support and guide said extension on said rail, said supporting and guiding means comprising a block and inwardly-facing conical rolls pivotally mounted on opposite 90 sides of said block and resting on said rail on opposite sides of the upper portion thereof, and ball-bearings for each of said rolls to connect the latter with said block.

19. In a typewriting machine of the fan-fold type, comprising a carriage, a carbon-carrier, and a rearward extension of said carriage on which carbon-carrier is reciprocable, said extension having downturned 100 side flanges, the combination with said extension, of a rail circular in cross-section, and means to support and guide said extension on said rail, comprising at each side of the extension a block secured at its outer 105 end to the inner face of the adjacent flange, and inwardly-facing conical rolls on opposite sides of said block to engage the upper portion of said rail on opposite sides thereof.

20. In a typewriting machine of the fan-fold type, comprising a carriage, a carbon-carrier, and a rearward extension of said carriage on which said carbon-carrier is reciprocable, said extension having downturned side flanges, the combination with 110 said extension, of a rail circular in cross-section, means to support and guide said extension on said rail, comprising at each side of the extension a block secured at its outer 115 end to the inner face of the adjacent flange, the upper portion of said block being cut away at the inner end thereof to form an upwardly-facing shoulder, and inwardly-facing conical rolls on opposite sides of said block to engage the upper portion of said rail on opposite sides thereof, and a guard having a flat portion fastened against said shoulder and a portion extending around said rail to prevent disengagement of the 120 rolls from the rail.

21. In a typewriting machine of the fan-fold type, comprising a carriage, a carbon-carrier, and a rearward extension of said carriage on which said carbon-carrier is reciprocable, said extension having down-turned side flanges, the combination with said extension, of a rail circular in cross-section, means to support and guide said extension on said rail, comprising at each side 5 of the extension a block secured at its outer end to the inner face of the adjacent flange, the upper portion of said block being cut away at the inner end thereof to form an upwardly-facing shoulder, and inwardly-facing 10 conical rolls on opposite sides of said block to engage the upper portion of said rail on opposite sides thereof, and a guard-member having one end secured on said shoulder and a downwardly-extending portion 15 secured on the inner end of said block and curved around said rail.

22. In a typewriting machine of the fan-fold type, comprising a carriage, a carbon-carrier, and a rearward extension of the carriage on which said carbon-carrier is mounted for reciprocation, the combination with said extension, of a rail, and a device 25 to support and guide said extension on said rail, said device comprising a block connected to said extension, a bolt passing through said block, an outwardly-facing cone on said bolt at each side of the block, an annular roll outside of each of said outwardly-facing cones and provided with an internal circular 30 groove of V-shaped cross-section, bearing balls in each of said grooves contacting with said outwardly-facing cones, an inwardly-facing cone on said bolt outside of each of said annular rolls and contacting with the 35 bearing balls in the groove of the adjacent roll, and means to hold the inwardly-facing cones on said bolt and thereby hold the other elements in operative position.

23. In a typewriting machine of the fan-fold type, comprising a carriage, a carbon-carrier, and a rearward extension of the carriage on which said carbon-carrier is mounted for reciprocation, the combination with said extension, of a rail, and a device 45 to support and guide said extension on said rail, said device comprising a block connected to said extension, a bolt passing through said block, an outwardly-facing cone on said bolt at each side of the block, an annular roll outside of each of said outwardly-facing cones and provided with an internal circular 50 groove of V-shaped cross-section, bearing balls in each of said grooves contacting with said outwardly-facing cones, an inwardly-facing cone on said bolt outside of each 55

of said annular rolls and contacting with the bearing balls in the groove of the adjacent roll, means to hold the inwardly-facing cones on said bolt and thereby hold the other elements in operative position, and a 65 curved guard attached to said block and extending partially around said rail to maintain the connection between said rolls and said rail.

24. In a machine of the class described 70 having a platen, a carriage comprising a rear paper-table to guide the web to the bottom of the platen, and denomination-selecting mechanism at the rear of the rear paper-table and projecting above the upper 75 edge of the latter, the combination with the platen, of means for displacing the platen upwardly to an abnormal extent to enable the straightening thereunder of a web extending substantially horizontally over the 80 denomination-selecting mechanism, said displacing means comprising a platen-displacing frame in which the platen is journaled and which is pivoted on said carriage at an abnormal distance from the axis of the platen 85 to enable an abnormal upward displacement of the latter, two gears at each end of the platen, one fixed to the platen and the other journaled in the adjacent end of the carriage, and a broad pinion mounted to rotate about 90 the pivotal axis of said frame, said pinion being oversized to correspond to the distance between the axis of the platen and the axis about which the platen-displacing frame is 95 swung.

25. In a machine of the class described, the combination with a platen, of a carriage therefor, comprising ends and a front bar, a platen-displacing frame including ends in which said platen is journaled, pivots for 100 the ends of the platen-displacing frame supported by the ends of the carriage, a broad pinion loosely mounted on each of said pivots and provided with a hub projecting at one side thereof, a pair of gears meshing with 105 said broad pinion, one of said gears being fixed to the platen and the other journaled in the adjacent end of the carriage, and means to limit the displacing movement of said platen-displacing frame, comprising at 110 each end of the carriage a bracket fixed on said front bar and having its rear end encircling said hub, and a stop for the adjacent end of the displacing frame projecting from said bracket adjacent said hub.
